CLAIM

The ornamental design for an audio amplifier, as shown and described.

DESCRIPTION

FIG. 1 is a perspective view of the front, top and left side of an audio amplifier showing our new design;

FIG. 2 is a front view thereof;

FIG. 3 is a rear view thereof;

FIG. 4 is a right side view thereof, the left side view being a mirror image of the right side view;

FIG. 5 is a top plan view thereof, the bottom plan view being identical to the top plan view; and,

FIG. 6 is a perspective view of the rear, top and right side thereof.

The broken line disclosure in the views forms no part of the claimed design.
